**ALL PLASTIC SHOTSHELL CASE WITH
TRANSVERSELY ORIENTED UNDULATIONS ON
OUTER CYLINDRICAL SURFACE**

BRIEF SUMMARY OF THE INVENTION

It has been found that all plastic shotshell cases wherein the transverse base wall and the cylindrical sidewall are integral of and in one piece with each other and are molded of any of a number of types of plastic such as linear polyethylene, will have more strength where the outer surface of the cylindrical sidewall is provided with a plurality of shallow undulations throughout the entire length of the cylindrical sidewall. Such undulations may be arranged in any of a number of patterns on the outer surface of the sidewall, and it has been found advantageous to arrange such undulations so that rings are formed extending circumferentially around the entire periphery of the cylindrical sidewalls, and all along the length of the sidewall case. The result is to strengthen the walls of the case, and this is caused, at least in part, because during the filling of the mold in which the shotshell case is formed, the plastic is flowed into the mold cavity in a direction longitudinally of the cylindrical sidewall being formed, and therefore across the undulations in the mold part forming the outer surface of the cylindrical sidewall. The molten plastic, during filling of the mold cavity, flows across these undulations in the mold part and causes some degree of laminating of the plastic during the flow which results in the increased strength of the plastic after the plastic is allowed to cure and harden.

It has been found that the undulations, oriented transversely of the longitudinal orientation of the cylindrical sidewall may be arranged in various patterns such as the rings extending circumferentially of the cylindrical sidewall, but the pattern may take the form of circles, dots, squares, knurls or any other convenient shape which nests together into an overlapping relation and which have at least a portion thereof extending transversely of the longitudinal orientation of the cylindrical sidewall.

BRIEF DESCRIPTION OF DRAWINGS

FIG. 1 is an enlarged elevation view, partly broken away, and in section, and illustrating a shotshell case according to the present invention, and illustrating the open mouth of the case closed with the usual star crimp.

FIG. 2 is a greatly enlarged longitudinal section view taken approximately at 2-2 in FIG. 1.

FIG. 3 is a fragmented detail view showing a small portion of the mold parts used in molding the all plastic shotshell case illustrated in FIGS. 1 and 2 to carry out the invention.

FIG. 4 is a greatly enlarged detail elevation view of the outer surface of a cylindrical shotshell sidewall, and illustrating a modified form of the invention.

FIG. 5 is a view similar to FIG. 4 and illustrating a second modified form of the invention.

DETAILED DESCRIPTION OF THE INVENTION

The all plastic shotshell case is indicated in general by numeral 10 and includes a transversely oriented base wall 11 and an elongate, substantially cylindrical sidewall 12. The base wall 11 and the sidewall 12 are molded integrally of and in one piece with respect to each other, and are formed of any of a number of plas-

tics suitable for molding all plastic shotshell cases, such as linear polyethylene, or an extrusion grade polyethylene material which is somewhat stiffer in consistency when injected into the mold cavity than other polyethylenes. The base wall of the shotshell case has an opening 13 therein to receive the primer of the shotshell, and the shotshell case has an open interior 14 for receiving the usual powder charge, wadding, and shot charge which, when added to the case and primer, make up the loaded shotshell. In the drawings, the integral closure 15 is shown in the position of a star crimp for illustration purposes, even though no powder or shot charge is contained in the shotshell.

The substantially cylindrical sidewall 12 is provided with a series of undulations 16a and 16b which are actually grooves and ribs or ridges respectively, extending circumferentially around the entire periphery of the substantially cylindrical wall 12. It is pointed out that the undulations 16a and 16b are provided on the outer surface of the sidewall, throughout substantially the entire length of the sidewall, and substantially strengthen the case sidewall.

It will be noted that the spacing between undulations may be varied at various locations along the length of the case sidewall, and in this form illustrated, the undulations 16a' and 16b' are smaller than the spacings between undulations along other portions of the case sidewall. The ribs and grooves formed by the undulations 16a' and 16b' form a more efficient sealing relationship with the chamber of the shotgun barrel when the case is fired, due to the extreme magnitude of gas pressure that builds up at the inner chamber 14 of the shotshell case upon firing of the shotshell and deformation of the plastic against the barrel wall at the rib-forming undulations 16b'.

FIG. 3 illustrates the molding of the shotshell case sidewall and shows a fragmented portion of the mold assembly which includes the mold part 20 which cooperates with the core 21 to define the mold cavity 22 therebetween. The mold cavity is correspondingly substantially cylindrically shaped to conform to the shape of the substantially cylindrical sidewall 12, and of course, the mold cavity 22 also extends across the end of the core to shape the plastic which forms the base wall 11 of the shotshell case. The mold part 20 has undulations 20a and 20b in its surface which form the outer surface of the substantially cylindrical sidewall 12. As illustrated, the molten plastic 23 is flowed in a direction longitudinally along the core 21 and longitudinally of the substantially cylindrical mold cavity 22, as indicated by the direction of arrow A. Because of this flow of the plastic material, the transversely oriented undulations 20a and 20b are encountered as the plastic flows in the direction of arrow A and because of the drag or restriction to flow at the undulations 20a, 20b, there is laminating of the plastic during the flow and a resultant strengthening of the case sidewall after the case is allowed to cure and harden. Of course, because of the undulations, the plastic, as it flows, has a shear location 23.1 as indicated by the dotted lines in FIG. 3, outwardly of which the plastic is retarded in movement and inwardly of which the plastic flows with full velocity in the direction of arrow A.

The resulting all plastic shotshell case 10 has an increased strength in the substantially cylindrical sidewall 12 due to the presence of the undulations and rings around the periphery thereof.

In the form illustrated in FIG. 4, the outer surface of the sidewall 12.1 is provided with a plurality of undulations 12.1a and 12.1b forming patterns on the outer surface of the sidewall in the form of a plurality of clustered circular annuli having a height similar to that of the undulations 16a and 16b illustrated in FIG. 1 wherein these undulations have a magnitude in a direction transversely of the case sidewall which is considerably less than the thickness of the sidewall. It will be noted that the circular annuli formed by the undulations 12.1a and 12.1b have portions oriented transversely of the elongate substantially cylindrical sidewall case 12.1

In FIG. 5 another form of the invention is illustrated wherein the substantially cylindrical sidewall 12.2 is provided with a plurality of undulations 12.2a and 12.2b arranged in a pattern forming closely nested squares or rectangles. It will be noted that portions of the undulations 12.2a and 12.2b are oriented transversely of the longitudinal orientation of the substantially cylindrical sidewall.

It should be understood that the undulations on the outer surface of the sidewall may be arranged in other patterns including dots, diamonds, knurls, or any of the other common geometric shapes, which have a portion oriented transversely or at least obliquely transversely of the longitudinal orientation of the sidewall case.

It will be seen that I have provided a new and improved all plastic shotshell case wherein the outer surface of the substantially cylindrical sidewall is provided with undulations arranged in a pattern with portions extending transversely of the elongate longitudinal orientation of the substantially cylindrical sidewall effecting a strengthening of the sidewall against outward expansion and rupture due to pressure developed within the case.

What is claimed is:

1. An all plastic shotshell case comprising:
a substantially cylindrical sidewall of molded plastic open at one end;
a base wall of molded plastic extending transversely of said sidewall at the opposite end thereof, said

sidewall and base wall being formed integrally as one piece, and said base wall having an opening therein to receive the primer of the shotshell; and

a plurality of undulations on the outer surface of said sidewall projecting outwardly therefrom, said undulations being formed integrally with said sidewall and extending in longitudinally spaced circular patterns over more than one half of the length of said sidewall up to and along said open end thereof, and said undulations being in the form of circumferentially extending rings of varying width in a direction along the length of said cylindrical sidewall, with the narrower rings being disposed adjacent said open end of said sidewall and being deformable against a shotgun barrel under the pressure developed within said shotshell case upon firing.

2. An all plastic shotshell as defined in claim 1 wherein:

said undulations comprise a plurality of closely clustered annuli of circular shape.

3. An all plastic shotshell comprising:
a substantially cylindrical sidewall of molded plastic open at one end;
a base wall of molded plastic extending transversely of said sidewall at the opposite end thereof, said sidewall and base wall being formed integrally as one piece, and said base wall having an opening therein to receive the primer of the shotshell; and

a plurality of undulations on the outer surface of said sidewall projecting outwardly therefrom, said undulations extending transversely with respect to said cylindrical sidewall in generally circular patterns over a substantial portion of the length of said sidewall up to and along said open end thereof, and said undulations being of varying width in a direction along the length of said sidewall with the narrowest undulations being disposed adjacent said open end of said sidewall.
